UNITED STATES PATENT OFFICE.

CLARK THOMPSON BRANT, OF CHARITON, IOWA.

SCREW-CAP FOR CANS, TANKS, &c.

SPECIFICATION forming part of Letters Patent No. 629,982, dated August 1, 1899.

Application filed December 30, 1898. Serial No. 700,737. (No model.)

To all whom it may concern:

Be it known that I, CLARK THOMPSON BRANT, a citizen of the United States, residing at Chariton, in the county of Lucas and State of Iowa, have invented a new and useful Improved Screw-Cap for Cans, Tanks, &c., of which the following is a specification.

The invention relates to improvements in caps for cans, tanks, and analogous receptacles.

The object of the present invention is to improve the construction of screw-caps for cans, tanks, and analogous receptacles, more especially the means employed for enabling the caps to be screwed on or off such cans and tanks, and to provide a simple, inexpensive, and efficient device adapted to be readily operated and capable of enabling screw-caps to be placed tightly on cans, tanks, and the like to effect an air-tight joint and of permitting such caps to be conveniently removed without injuring them or the receptacles.

The invention consists in the construction and novel combination and arrangement of parts, as hereinafter fully described, illustrated in the accompanying drawings, and pointed out in the claims hereto appended.

In the drawings, Figure 1 is a perspective view of a portion of a receptacle provided with a screw-cap constructed in accordance with this invention, the lever being in engagement with the lugs. Fig. 2 is a plan view of the same. Fig. 3 is a detail perspective view of one of the lugs.

Like numerals of reference designate corresponding parts in all the figures of the drawings.

1 designates a metal screw-cap engaging a receptacle 2 in the usual manner and provided at diametrically opposite points with vertical metal lugs or flanges 3, arranged parallel with each other and located adjacent to the periphery of the screw-cap and adapted to be engaged by a lever 4. The lugs or flanges are preferably constructed of sheet metal folded upon itself to form a stiffened central portion of two plies and bent outward from the base of the same to form attachment flanges or portions, which are soldered or otherwise secured to the upper face of the cap. The vertical end edges of the flanges are provided with series of recesses or notches, form-

ing teeth 5, which are adapted to engage the edges of the lever 4, and the latter is preferably constructed of wood in order that the 55 said teeth may positively engage the same. The lever is held against longitudinal movement when in engagement with the lugs by notches or recesses 7 and 8, located adjacent to the end portions of the lever and disposed 60 at opposite sides of the same, the lever being adapted to project from both sides of the screw-cap, so that it can be readily handled in screwing and unscrewing the same. One end of the lever is shaped to form a handle 9, 65 and by providing the recesses or notches 7 and 8 at both edges of the lever the latter is rendered reversible and is adapted to engage the lugs at either side and can be arranged quickly in position for rotating the screw-cap 70 in either direction without changing it from one side to the other.

The invention has the following advantages: The device, which is simple and comparatively inexpensive in construction, is applicable to the screw-caps of tanks, cans, and analogous receptacles, and the lever which engages the lugs may be constructed of wood and is adapted to be readily reversed at either side of the screw-cap for rotating the latter 80 to screw it on or remove it from a receptacle. The notches of the lever prevent the same from slipping longitudinally when in engagement with the lugs or flanges, and the teeth or recesses of the same bite into the wood and 85 prevent the lever from slipping upward. These teeth also enable the cover to be unscrewed or placed on a receptacle by any ordinary piece of board, such as a part of the cover of a wooden box, and they will prevent 90 the same from slipping out of engagement with the lugs or flanges.

Changes in the form, proportion, and minor details of construction may be resorted to without departing from the spirit or sacrifice 95 any of the advantages of this invention.

What is claimed is—

1. In a device of the class described, the combination with a metal screw-cap, of a pair of lugs or flanges mounted upon the top of the 100 cap and located within the periphery thereof and provided at each end with a straight vertical edge having notches or recesses forming teeth adapted to bite into a wooden bar,

and capable of permitting the same to be reversed to engage either edge of the lug, whereby the cap may be screwed on or off, substantially as described.

- 5 2. In a device of the class described, a reversible lever provided at one end with a handle and adapted to engage the lugs of a screw-cap, said lever being provided at its side edges with notches or recesses arranged in 10 pairs and adapted to receive the said lugs in

either position of the lever and capable of preventing the latter from slipping longitudinally, substantially as described.

In testimony that I claim the foregoing as my own I have hereto affixed my signature in 15 the presence of two witnesses.

CLARK THOMPSON BRANT.
